UNITED STATES PATENT OFFICE

WATKINS BENERMAN, OF EL PASO, TEXAS

ILLUMINATED SIGN

Application filed June 12, 1929. Serial No. 370,329.

My invention relates generally to illuminated display devices such as signs, and more particularly to signs in which a plurality of illuminating elements are arranged close together and adapted for successive illumination to create the illusion of movement of light.

Heretofore, such signs have been constructed to comprise a plurality of incandescent lamps arranged in various relative positions and means for switching the individual lamps or groups of lamps on and off according to a predetermined sequence. Because of the fact that these heretofore constructed signs have included a large number of individual lamps, the electrical connections necessary for producing the desired sequence of illuminations of the various lamps have necessarily been complicated and correspondingly expensive both in original cost and in the cost of maintenance. When it is realized that a sign of even modest proportions includes several hundreds of lamps, it will be readily appreciated that the construction of a sign capable of producing results similar to the results produced by such heretofore constructed signs, but entailing a much simpler arrangement of parts, electrical connections, and switching apparatus, will be an important step forward in the art.

As far as I am aware, signs of the above described general character have always been made up of a plurality of incandescent lamps, and in such signs no use has been made of luminous electric discharge lamps of the kind including a translucent tube filled with neon or other similar rarefied gas adapted to produce a luminous glow upon the passage of an electric current through the tube. I have found that electric discharge lamps of this kind may be so arranged in an illuminated sign as to be adapted to create the illusion of movement of light, and that the effects produced are more attractive than the effects obtainable in signs comprising a number of spaced individual lights.

An object of my invention is therefore to provide an illuminated display device com-

prising a plurality of gas filled tubes arranged in a manner to glow upon the passage of an electric current therethrough to thus create the effect or illusion of movement of light. Other objects will become apparent from the description which is to follow.

In the drawings, Figure 1 is a diagrammatic view showing an arrangement of twelve tubes arranged in four banks of three tubes each, and electrical connections and switching apparatus for illuminating the tubes in desired predetermined sequence;

Figure 2 is a perspective view of three tubes arranged in a manner to create the illusion of substantially linear movement of light when the tubes are illuminated in succession;

Figure 3 shows in perspective a modified arrangement of three tubes in which the successive lighting of the tubes creates the illusion of movement of light along a straight thin line;

Figure 4 shows in perspective a modified arrangement in which a plurality of tubes are so individually formed and arranged relative to one another that a lighting of the respective tubes in succession will create the effect of oscillation of light about an axis;

Figure 5 is a sectional view taken on the line 5—5 of Figure 4;

Figure 6 shows in perspective an arrangement of six tubes arranged spirally about a common axis and adapted to produce the illusion of movement of light in a spiral direction;

Figure 7 is a view similar to Figure 6 except that three tubes only are employed;

Figure 8 is a perspective view of an arrangement similar to that shown in Figure 3 except that two tubes only are used.

My invention may be embodied in signs or other display devices including various different arrangements of electric discharge lamps. In general, a sign constructed in accordance with my invention includes a plurality of gas filled tubes adapted to produce a luminescent glow upon the passage of an electric current therethrough, the tubes being arranged close together and in most

cases extending in the same general direction. Each of the tubes is provided with alternate light radiating and opaque portions, the light radiating portions of the tubes being spaced from each other in most but not all cases in the direction in which the tubes extend. A source of electric power of suitable potential is connected to the opposite ends of the respective tubes and automatic switching mechanism is provided for alternately lighting and extinguishing the several tubes in succession. In this way the light visible at the light radiating portions of one tube through which current is being passed will, when current is shut off from that tube and caused to flow through the next tube, appear to move to the adjacent light radiating portion of the tube next lighted. In this manner the illusion of movement of light will be made to produce various different effects by forming the individual tubes and locating them relative to each other in a manner designed to produce the desired effects.

With more particular reference to the illustrated embodiments of my invention, I have shown in Figure 1 a simple arrangement of tubes adapted to create the illusion of movement of light, and the appertaining electrical connections for lighting the tubes in desired sequence.

The sign embodying my invention and illustrated in Figures 1 and 2 includes a sign proper A, electrical connections B for furnishing electricity to the tubes comprising the sign proper, and an automatic switching mechanism C.

The sign proper comprises four banks, 1, 2, 3, and 4, of tubes, each bank including three tubes 5, 6, and 7. Beginning with the bank 1 shown on the left as viewed in Figure 1, the upper ends of the tubes 5, 6, and 7 thereof are respectively connected to the left hand ends of the corresponding tubes 5, 6, and 7 of the bank 2. The other ends of the tubes 5, 6, and 7 in bank 2 are, in a similar manner, connected to the upper ends of corresponding tubes 5, 6, and 7 of the bank 3, and the other ends of the tubes in the bank 3 are connected to the right hand ends of the corresponding tubes of the bank 4.

As shown in Figure 2, each bank of tubes comprises three individual tubes arranged to extend in the same general direction, namely, from left to right as viewed in the plane of the drawings. Each of the tubes includes a plurality of substantially V-shaped sections 9 united by connecting portions 10. Each V-shaped section includes light radiating and opaque portions 11 and 12 which are respectively located on opposite sides of the apex of the section. The apex of each section and the connecting portions 10 between adjacent sections of each tube are formed to extend a short distance perpendicularly of

the planes in which the light radiating and opaque portions of the tubes lie. It will be noted that all of the light radiating portions of each tube lie in a common plane and that all of the opaque portions of each tube lie in a plane parallel to and spaced from the first plane.

The tubes are so arranged relative to each other that, when viewed from the front of the sign, the light radiating portions of each tube cross in front of the opaque portions of the other tubes so that, when any tube is lighted, the illumination displayed by the light radiating portions will not be shut off from view by any part of an opaque portion. It will be observed that the intermediate light radiating portions of any of the tubes 5, 6, and 7 are disposed between adjacent light radiating portions of another of the tubes. For instance, the first light radiating portion from the left of the tube 6 as viewed in Figure 2 is disposed between the first and second light radiating portions of the tube 5 from the left as viewed in Figure 2. In a like manner, the second light radiating portion of the tube 5 is disposed between the first and second light radiating portions of the tube 6. It will be apparent that, when the tubes 5, 6, and 7 are lighted in succession, light will appear to move from the light radiating portions of the tube 5 to the light radiating portions of the tube 6, and thence to the light radiating portions of the tube 7, thereby creating the illusion of movement of a continuous band of light toward the right as viewed in the drawings. It is also apparent that, if desired, the light may be made to appear as though moving from right to left by simply illuminating the tubes in the reverse order, namely, 7-6-5. If desired, switching mechanism could be arranged to illuminate the tubes in the following sequence, 5 and 6 together, 6 and 7 together, 7 and 5 together, 5 and 6 together, 6 and 7 together, 7 and 5 together, and so on. In this way, the adjacent light radiating portions of two of the tubes would be lighted at the same time, and a slightly different effect would be produced, although the band of light would still appear to move from left to right. It will be noted that, since each of the tubes 5, 6, and 7 comprises a plurality of spaced light radiating portions, and since the associated tubes have their light radiating portions in staggered relation and arranged in the order 5-6-7, then repeating 5, 6, and 7, then again repeating, and so on, these light radiating portions are arranged in repeating series, which arrangement makes possible the creation of movement of a continuous band of light instead of the movement of a point of light.

It is to be understood that the particular construction of the tubes may be of any

suitable kind, with the exception that the shape of the tubes should be arranged in accordance with the foregoing description or that of some modification embodying the same general principle. Tubes filled with neon or other rarefied gas and provided with suitable electrodes at the ends of the tubes are of well known construction and need not be described in detail.

The ends of the tubes are connected by a power line 13 to any suitable source of electricity. In order to intermittently furnish current to the tubes in succession, I provide a motor 14 connected to the source of electricity, reduction gearing 15 driven by the motor, and a three-segment commutator 16 in turn driven by the reduction gearing. A rheostat or starting box 17 is interposed between the motor and one side of the power line 13 for controlling the speed of the motor. A transformer 18 is interposed between each tube and the source of electricity in order to step up the voltage to the desired potential. One side of the primary winding of each transformer is connected to one side of the power line by a conductor 19, and the other side is connected to one of the commutator brushes by a conductor 20. The secondary winding of each transformer is connected to opposite terminals of one of the tubes by conductors 21-21. While I have illustrated one form of current-supplying means, it is to be understood that this illustration is given merely as an aid in understanding the invention, and that any means for supplying an intermittent flow of current to the tubes successively would suffice.

Figure 3 illustrates a modified arrangement of tubes adapted to create the effect of movement of light along a thin straight line. In this modification three tubes 22, 23, 24 are employed, each of the tubes including spaced off-set or U-shaped light radiating portions 25-25 and intervening opaque portions 26. It will be observed that the tubes are so arranged relative to each other that the light radiating portions 25 of the respective tubes extend in substantially the same straight line and are arranged in repeating series such as that described in connection with the construction illustrated in Figures 1 and 2. By illuminating the tubes in succession and then repeating, light will appear to move from left to right as viewed in Figure 3 in a thin straight line.

Figure 8 illustrates an arrangement similar to that shown in Figure 7 with the exception that two tubes 27 and 28 are employed, each having spaced light radiating portions 29 and intervening opaque portions 30 respectively. It is apparent that, when the tubes 27 and 28 are alternately illuminated and extinguished, in succession, light will appear to move from the light

radiating portions of one tube to the other and thence back to the first tube. If desired, any number of tubes within reasonable limits could be employed in an arrangement such as those shown in Figures 3 and 8 to produce various different illusions of movement.

In the arrangement illustrated in Figures 4 and 5, four tubes 31, 32, 33, and 34 are so arranged that, when the tubes are alternately lighted and extinguished in a predetermined sequence, light will appear to oscillate about an axis. In this arrangement the several tubes extend in the same general direction and are individually of zig-zag formation, each tube comprising a plurality of connected, light radiating, outwardly bowed or substantially V-shaped sections 35 connected by intermediate inwardly bowed opaque portions 36, the V-shaped sections of the several tubes being transversely aligned and arranged in pairs of directly opposite sections. These tubes are radially disposed about a line extending longitudinally and centrally of the tubes and are angularly displaced from one another as shown in Figure 5. By first illuminating the tube 31, then the tube 32, then the tube 33, and then the tube 34, light will appear to swing downwardly from the tube 31 to the tube 34. By then lighting the tubes in the reverse order, light will appear to swing upwardly from the tube 34 to the tube 31, and by repeating this sequence of illumination there will be produced an apparent continuous oscillation of light about a horizontal axis. If it is desired to create the effect of rotation of light about an axis, the tubes will be illuminated in the order 31-32-33-34, then repeating 31-32-33-34 and so on. The tubes 31-32-33- and 34, instead of being angularly displaced from each other, may, if more convenient for manufacturing considerations, be arranged to all lie in a common plane. With this arrangement the V-shaped portions of the two inner tubes 32 and 33 would extend laterally away from each other to a lesser degree than the two outer tubes 31 and 34. When either of the two arrangements described above are employed for producing the effect of radiation or oscillation of light about an axis it is desirable that the outer extremities of the outwardly bowed sections 35 of the tubes 31 and 34 which it will be observed, constitute outer tubes, lie in a common plane as shown in Figure 5. It is also desirable that the projections of the outwardly bowed sections of the tubes 32 and 33, which constitute inner tubes, upon the plane in which the outer extremities of the outer tube sections lie be disposed between the opposite sections of the respective pairs of outer tube sections.

It is apparent that the tubes might be formed to include a plurality of connected

curved sections, rectangular portions, or U-shaped sections, and that by using tubes of these various different shapes the same effect of oscillation of light will be obtained. 5 The herein illustrated and described arrangement of four tubes for producing the effect of oscillation of light about an axis exemplifies a practical embodiment of this 10 effect of the invention, but the general effect may be produced by means of any number of tubes greater than two and within practical limits. If two tubes only are employed, as for instance the tubes 31 and 34, the effect produced will be that of 15 light flashing back and forth between the tubes.

Figure 6 illustrates a further modification in which six tubes 38, 39, 40, 41, 42, and 20 43 are spirally arranged about a common axis. In this arrangement, the individual tubes are provided with alternate light radiating and opaque portions 44 and 45, respectively, the light radiating portions of the several tubes being longitudinally staggered relative to one another. By lighting 25 the tubes in succession, light will appear to move in a spiral direction, the effect produced being similar to that of a rotating striped barber's pole.

30 Figure 7 illustrates an arrangement of spirally disposed tubes similar to that shown in Figure 6, with the exception that only three tubes 46, 47, and 48 are employed. In this construction, each tube includes alternate light radiating and opaque portions 49 and 50 respectively arranged in a manner 35 similar to that shown in Figure 6.

From the foregoing, it will be apparent 40 that the number of tubes, the shape of each individual tube, and the relative arrangement of the light radiating portions of the several tubes may be varied in order to obtain a wide variety of results. While, in 45 describing several of the forms embodying my invention, I have stated that the tubes shall be lighted successively and one at a time, it is to be understood that the sequence of illumination may be varied in accordance with the results which are desired, and that, 50 where a comparatively large number of tubes is employed, it will be possible to further increase the variety of results obtainable by the lighting of tubes in groups of two or more at the same time, which 55 lighting is followed by the lighting of other groups of tubes. It is also apparent that the light radiating portions of the several tubes constituting a bank of tubes may be treated so as to display vari-colored illumination, and that by the combination of 60 colors and different sequence of illumination practically any desired number of different lighting effects may be obtained.

A sign constructed in accordance with my 65 invention is capable of producing effects

heretofore not obtainable with signs using a large number of incandescent lights, and is of simple construction entailing the use of much simpler electrical equipment than a sign constructed in accordance with heretofore existing practice. It is to be understood that my invention is not applicable to signs only, but that it may also be embodied in illuminated designs or decorations of various different kinds.

I claim:

1. In an illuminated sign, the combination of a plurality of gas filled tubes arranged close together and extending in the same general direction, and each adapted to glow upon the passage of an electric current therethrough, each tube being of zig-zag shape and comprising a plurality of connected and substantially V-shaped sections, the respective sections of the tubes being substantially similar and arranged in transverse alignment and disposed in different positions and in substantially radial relation about a line extending longitudinally and substantially centrally of the sign.

2. In an illuminated sign, the combination of a plurality of gas filled tubes arranged close together and extending in the same general direction, and each adapted to glow upon the passage of an electric current therethrough, each tube being of zig-zag shape and comprising a plurality of connected and substantially V-shaped sections, the respective sections of the tubes being substantially similar and arranged in transverse alignment and disposed in different positions and in substantially radial relation about a line extending longitudinally and substantially centrally of the sign, the outer tubes being located in substantially the same general plane and the inner tubes being disposed substantially entirely on one side of said general plane.

3. In an illuminated sign, the combination of a plurality of gas filled tubes arranged close together and extending in the same general direction, and each adapted to glow upon the passage of an electric current therethrough, each tube being of zig-zag shape and comprising a plurality of connected and substantially V-shaped sections, the respective sections of the tubes being substantially similar and arranged in transverse alignment and disposed in different positions and in substantially radial relation about a line extending longitudinally and substantially centrally of the sign, and means for successively illuminating the tubes whereby the desired effect is obtained.

4. In an illuminated sign, the combination of a plurality of gas filled tubes arranged close together and extending in the same general direction, and each adapted to glow upon the passage of an electric current therethrough, each tube being of zig-zag

shape and comprising a plurality of connected and substantially V-shaped sections, the respective sections of the tubes being substantially similar and arranged in transverse alignment and disposed in different positions and in substantially radial relation about a line extending longitudinally and substantially centrally of the sign, the outer tubes being located in substantially the same general plane and the inner tubes being disposed substantially entirely on one side of said general plane, and means for successively illuminating the tubes whereby the desired effect is obtained.

In testimony whereof, I have hereunto
subscribed my name.

WATKINS BENERMAN.
